OIL COOLER

Franz X. Reimspiess, Stuttgart, Germany, assignor to Dr. ing. h. c. F. Porsche, K.-G., Stuttgart-Zuffenhausen, Germany, a company of Germany

Application October 4, 1938, Serial No. 233,214
In Germany October 6, 1937

4 Claims. (Cl. 123—171)

This invention relates to oil coolers and particularly to the arrangement of oil coolers associated with internal combustion engines of the type cooled by blowers.

In the case of high speed internal combustion engines operating for long periods under full load as occurs frequently in automotive service, the lubricating oil is depended upon to carry away some of the heat of the engine, especially in the case of air cooled engines in which a considerable part of the heat is developed at points not readily accessible to the current of the cooling medium, such as air. As will be readily understood, it becomes necessary in such cases to provide for proper cooling of the lubricating fluid.

It is an object of this invention to avoid the disadvantages of prior constructions by dividing the stream of cooling air into several partial air streams, one of which is passed through the oil cooler.

Another object is to provide such a construction in which one of said air streams is passed through the oil cooler and also into contact with a part of the engine to be cooled.

Another object is to provide a construction having minimum air resistance and minimum eddy currents so that the various engine parts may be effectively and reliably cooled.

The division of the cooling air current has the result that a separate current may be supplied for each cylinder or each group of cylinders.

Another object is to so divide the air stream that a single cylinder or a cylinder group may be divided into several separate zones, each cooled by an individual air stream.

Another object is to divide the air stream into several individual streams, some of which are directed to cool certain engine parts and another, appropriately enlarged, air stream is directed to cool the oil cooler and also certain other parts of the engine.

Another object is to provide a construction having minimum air resistance and maximum certainty of air flow so that all parts will be reliably cooled.

Another object is to provide a construction in which the various air stream guiding members may be easily removed for exposing and giving access to the oil cooler.

Another object is to provide a surrounding casing for said air cooling devices which carries at least some of the guide surfaces for dividing and directing the air streams so that upon removal of the casing said attached means will be

removed therewith, thus facilitating access to the underlying parts.

Other objects will appear from the following description of an illustrative embodiment of the invention taken together with the attached drawing which shows in vertical section one form of the invention as applied to an opposed engine.

In said drawing, the numeral 1 represents the usual crank case provided with crank shaft 2 and carrying the two cylinders 3 and 4 whose cylinder heads are designated as 5 and 6, respectively. Above the crank case 1 is journaled the blower wheel 7 whose shaft 8 is driven from the crank shaft 2 by any suitable means. The guiding surface formed comprising the guiding vanes 9, 10, and 11, divides the cooling air stream into three partial air streams 12, 13, and 14. The partial air streams 12 and 13, as shown, pertain to the left cylinder 3, 5, and the partial air stream 14 pertains to the right cylinder 4, 6. In the partial air stream 12 lies the oil cooler 15 and thereafter the cylinder 3 to be cooled. The head 16 of the oil cooler is preferably covered by a directing vane 9. The foot 17 of the oil cooler is joined to the guiding vane 11 in such a manner as to minimize the air resistance. The sides 18 and 19 of the head 16 and the foot 17 face the cooling air current and are formed in accordance with the laws of streamlining. The partial air current 12, after flowing through the oil cooler 15, is preferably divided by means of the guiding vane 20 into the partial air streams 21 and 22. The partial air stream 21 cools the relatively lightly heated cylinder 3, the air stream 22 joining with the partial air current 13 and together they cool the cylinder head 5 which must be especially well cooled. Due to the distribution of the guide vanes 10 and 11 around the circumference of the blower wheel 7, the left cylinder 3, 5, in whose cooling air current the oil cooler lies, receives considerably more cooling air than is supplied then to the right cylinder 4, 6. The cooler 15 is fastened down upon an extension of the crank case by means of its foot 17. The connection of the oil inlet conductor 24 and the oil outlet conductor 25 preferably is effected through the attaching surface 26. The cover 27 surrounding the entire air cooling device is separate from the guide vanes 28 and 29 which are attached to the cylinders and it is connected therewith only by screws 30 and 31 so that it can be readily taken off; the guiding vanes 9, 10 and 20 are firmly interconnected with the cover 27 so that they will be

removed upon removal of the cover and the oil cooler 15 will be completely exposed.

This invention makes possible not only the use of a compactly built oil cooler which can be produced with less expense and lower weight, but also permits the provision, at low cost, of a blower for readily cooling the motor with the least amount of driving power. Insertion and taking out of the oil coolers is easy and quick. It is completely protected; it needs no additional space; and does not hinder the accessibility of the other parts of the internal combustion engine.

This invention is usable with Diesel and other engines as well as with intermediate forms. The invention is applicable equally for in-line, radial, and opposed engines. For this reason duplicating is possible as, for example, two or more oil coolers, or in special cases, several blowers may be used. The special formation of the oil cooler is unimportant. It can, for example, be made as a tubed or webbed cooler and its head can be so shaped that it itself forms a guiding vane. Its connection can be brought about in any desired manner, for example by means of two tubes resting in the crank case which also, at the same time, form a part of the oil circuit. Finally, the formation of the cover and how the oil cooler is made readily accessible is of no importance in this connection. It is merely to be remembered that it must be readily removable and so divided that it consists of readily removable parts which open up the oil cooler for testing and possible exchange.

It will be noted that the construction shown and described will serve admirably to accomplish the objects stated above. It is to be understood, however, that the construction disclosed above is intended merely as illustrative of the invention and not as limiting as various modifications therein may be made without departing from the invention as defined by a proper interpretation of the claims which follow.

I claim:

1. In an air-cooled internal combustion engine including a plurality of cylinders and a power shaft, a blower driven by said power shaft, an oil cooler, a plurality of delivery ducts leading from said blower, one of which delivers cooling air to a cylinder and another of which delivers cooling air to said oil cooler and thereafter to another cylinder, and third duct which delivers air directly to said second-mentioned cylinder, said duct being so positioned relatively to said blower and so dimensioned that the second and third ducts together receive more air from the blower than said first duct, whereby the total cooling effect from said air upon both cylinders is substantially the same despite the inclusion of the oil cooler in the second duct.

2. In an air-cooled internal combustion engine including a plurality of cylinders and a power shaft, a blower driven by said power shaft, an oil cooler, a plurality of delivery ducts leading from said blower, one of which delivers cooling air directly to cylinder and another of which delivers cooling air to said oil cooler and thereafter to another cylinder, the said ducts being so positioned relatively to said blower and so dimensioned that the amount of air delivered to each of said cylinders is such that each of said cylinders receives the same amount of cooling, despite the inclusion of the oil cooler in the other duct.
3. In an air-cooled internal combustion engine including a plurality of opposed horizontal cylinders extending oppositely from a crank case, and a power shaft in said crank case, a blower located above said cylinders and driven by said power shaft, an oil cooler, a plurality of delivery ducts lying in the plane of rotation of said blower leading from said blower, one of which ducts delivers cooling air directly to a cylinder downwardly upon said cylinder, and another of which delivers cooling air to said oil cooler and thereafter to another cylinder downwardly upon said second cylinder, said ducts being so positioned relatively to said blower and so dimensioned that the one delivery duct receives less air and the other more air from the blower, whereby the total cooling effect from said air upon both cylinders is substantially the same, despite the inclusion of the oil cooler in said other duct.
4. In an air-cooled internal combustion engine including a plurality of opposed horizontal cylinders extending oppositely from a crank case, and being provided with radially extending annular cooling fins, and a power shaft in said crank case, a blower located above said cylinders and driven by said power shaft, an oil cooler, a plurality of delivery ducts lying in the plane of rotation of said blower leading from said blower, one of which ducts delivers cooling air to a cylinder downwardly thereupon and between its cooling fins, and another of which delivers cooling air to said oil cooler and thereafter to another cylinder downwardly thereupon and between its cooling fins, and a third duct which delivers air directly to said second-mentioned cylinder downwardly thereupon and between other of its cooling fins, said ducts being so positioned relatively to said blower and so dimensioned that the second and third ducts together receive more air from the blower than said first duct, whereby the total cooling effect from said air upon both cylinders is substantially the same despite the inclusion of the oil cooler in the second duct.
